Patented Nov. 9, 1965

202,810

CLEANING MACHINE FOR VEHICLES OR THE LIKE

Elvin R. Goodrich, Oklahoma City, Okla.

Filed Mar. 1, 1965, Ser. No. 84,620

Term of patent 14 years

(Cl. D49—2)

FIGURE 1 is a top plan view of a cleaning machine for vehicles or the like, showing my new design;

FIGURE 2 is an elevational view of one side thereof;

FIGURE 3 is an elevational view of another side thereof;

FIGURE 4 is a bottom plan view thereof;

FIGURE 5 is an elevational view of another side thereof;

FIGURE 6 is an elevational view of another side thereof;

FIGURE 7 is a top plan view of a modified form of the design shown in FIGS. 1-6;

FIGURE 8 is a perspective view showing one side thereof;

FIGURE 9 is a perspective view showing another side thereof;

FIGURE 10 is a perspective view showing another side thereof;

FIGURE 11 is a perspective view showing still another side thereof; and

FIGURE 12 is a bottom plan view thereof.

This application is a continuation-in-part of my co-pending application Serial No. 75,578, filed June 28, 1963 now abandoned.

I claim:

The ornamental design for a cleaning machine for vehicles or the like, as shown and described.
